UNITED STATES PATENT OFFICE.

ALFRED J. REEDY, OF BATTLE CREEK, MICHIGAN, ASSIGNOR TO A-B STOVE COMPANY,
OF BATTLE CREEK, MICHIGAN.

STOVE.

Application filed October 10, 1923. Serial No. 667,665.

To all whom it may concern:

Be it known that I, ALFRED J. REEDY, a citizen of the United States, residing at Battle Creek, county of Calhoun, State of Michigan, have invented certain new and useful Improvements in Stoves, of which the following is a specification.

This invention relates to improvements in stoves.

10 The main objects of this invention are:

First, to provide an improved stove in which the parts may be enameled and are so arranged and assembled that the enamel is not likely to be injured in shipping and

15 handling the stove.

Second, to provide in a stove an improved oven structure formed mainly of sheet metal, and at the same time being substantial and strong and having a substantial appearance.

20 Third, to provide an improved stove in which the parts are economical to produce, and easily and quickly assembled.

Objects pertaining to details and economies of my improved structure will definitely appear from the detailed description to follow.

I accomplish the objects of my invention by the devices and means described in the following specification. The invention is clearly defined and pointed out in the claims.

A structure embodying the features of my invention is clearly illustrated in the accompanying drawing forming a part of this application, in which:

35 Fig. I is a front perspective view of a gas stove embodying the features of my invention.

Fig. II is a fragmentary rear perspective view.

40 Fig. III is a detail vertical section on a line corresponding to line 3—3 of Fig. I.

Fig. IV is a detail horizontal section on a line corresponding to line 4—4 of Fig. I.

Fig. V is a fragmentary front elevation 45 of the oven top and one of its side walls showing the relation of these parts.

Fig. VI is a detail horizontal section on a line corresponding to line 6—6 of Fig. V.

Fig. VII is a fragmentary perspective 50 view of the oven top and one of the side walls in disassembled relation.

Fig. VIII is a detail horizontal section on a line corresponding to line 8—8 of Figs. I and II.

Fig. IX is a detail section on a line corresponding to line 9—9 of Fig. II.

In the drawing the sectional views are taken looking in the direction of the little arrows at the ends of the section lines and similar numerals of reference refer to similar parts throughout the several views.

Referring to the drawing, the stove illustrated comprises an oven section designated generally by the numeral 1 and an open top section designated generally by the numeral 2, the open top section being provided with a back wall 3 having a shelf 4 at the top thereof.

The side walls 5 of the oven are provided with inturned flanges 6 at their upper edges 70 and inturned flanges 7 at their front edges, the flanges 7 being angled, that is, they have inwardly projecting arms 8. The top 9 has downwardly projecting side flanges 10 which overlap the upper ends of the side walls 5, these side walls being inwardly offset at 11 to receive the flanges 10, see Fig. VII.

The top has a downwardly projecting flange 12 at its front edge, this flange 12 being an angled flange having an inwardly 30 projecting arm 13'. The flange 12 overlaps the upper ends of the flanges 7 of the side walls, the inwardly projecting arms of the flanges 7 and 12 being cut away to permit their overlapping engagement. The upper 35 ends of the flanges 7 are inwardly offset at 13 providing seats for the ends of the flanges 12.

Gaskets 15 of asbestos or other heat resisting material are arranged between the 90 overlapping parts as shown in Fig. VI, the bolts 16 securing the overlapping flanges with the gaskets between them.

The side walls and top are provided with inturned flanges 17 at their rear ends, the 95 rear wall 18 being arranged within these flanges and secured thereto by the bolts 19, the nuts 20 on the bolts clamping these parts together.

The front cross piece 21 is, in the structure illustrated, of channel cross section and has inwardly offset ends 22 arranged within the flanges 7, the inturned arms 8 of these flanges being cut away to receive the ends 22. Gaskets 23 are arranged between these 100 ends 22 and the flanges, clamping bolts 24 securing the parts together with the gaskets between them.

The side wall linings 25 and the top 26 are arranged with their forward ends behind the flanges at the front edges of the side and front walls. The rear lining 27 is provided with flanges at its edges spacing it from the back wall 18.

The top 9 is notched at 28 to receive the portion 29 of the side walls between the offsets 11 and 13 thereof so that the flanges of the top are flush with the outer sides of the side walls and their front flanges. The corner irons 43 are shaped to fit over the upper corners of the oven and are secured by bolts 30 arranged through holes 31 in the top and side walls, a part at least of these holes being of such diameter that a limited movement of the parts is permitted, thus preventing twisting stresses which might crack the enamel.

20 The oven door 32 is supported by the hinge members 33 while the broiler door 34 is supported by the hinge members 35 secured at the lower ends of the flanges of the oven side walls.

25 The back 3 has an outwardly offset portion 36 at one end engaged with the bolts 19 at the outside of the nuts 20, nuts 37 securing this back in place. The shelf 4 is provided with a back 38. To secure this back the bolts 39 are clamped to the back 4 by means of the nuts 40, concavo convex washers 41 being arranged on the bolts to engage the back and clamp it thereon by the nuts 42. This provides an effective 37 means for supporting the shelf back 38 and permits its being attached without danger of breaking the enamel.

By thus forming and arranging the parts the cost of manufacture is very substantially 40 reduced, the parts may be enameled and assembled without danger of injuring the enamel and also may be shipped or transported with a minimum of damage to the enameled parts.

45 Having thus described my invention what I claim as new and desire to secure by Letters Patent is:

1. An oven comprising side walls having inwardly projecting flanges at their rear, top and front edges, a top having downwardly projecting flanges at its rear, side and front edges disposed with its side flanges overlapping the upper end of the side walls and with its front flange overlapping the upper 55 ends of said side wall front flanges, said front flanges of said top and side walls being angled and cut away at their ends to permit their overlapping engagement, a channel-shaped front cross member having 60 inwardly offset ends disposed on the inner sides of said side wall front flanges, the inwardly projecting arms of said front flanges being notched to receive the ends of said cross member, gaskets arranged between 65 said overlapping front flanges and cross

member, corner irons bolted to said top and side walls and to their said front flanges, a back wall disposed within the rear flanges of said top and side wall, and inner top and side walls having their front ends engaged with the inwardly projecting arms of said front flanges. 70

2. An oven comprising side walls having inwardly projecting flanges at their rear, top and front edges, a top having downwardly 75 projecting flanges at its rear, side and front edges disposed with its side flanges overlapping the upper ends of said side flanges thereof, said front flanges of their top and side walls being angled and cut away at 80 their ends to permit their overlapping engagement, corner irons bolted to said top and side walls and to their said front flanges, a back wall disposed within the rear flanges of said top and side wall, and inner top and side walls having their front ends engaged with the inwardly projecting arms of said front flanges. 85

3. An oven comprising side walls having inwardly projecting flanges at their front 90 edges, the front flanges of said top and side walls being angled, the upper ends of said side walls and of their said front flanges being inwardly offset providing seats for the overlapping side and front flanges of 95 said top, the inwardly projecting arms of said top and side wall front flanges being cut away at the ends thereof permitting the overlapping engagement of such flanges, said top wall being notched at its corner to 100 receive the side wall between the seats therein, a front cross member disposed facing inwardly and having inwardly offset ends disposed on the inner sides of said side wall front flanges, the inwardly projecting arms 105 of such flanges being cut away to receive the said offset ends, gaskets arranged between said overlapping front flanges, securing bolts for said overlapping front flanges, and corner irons bolted to said top 110 and side walls and to said front flanges thereof.

4. An oven comprising side walls having inwardly projecting flanges at their front edges, a top having downwardly projecting 115 flanges at its front and side edges, the upper ends of said side walls and of their said front flanges being inwardly offset providing seats for the overlapping side and front flanges of said top, said top wall being notched at its corners to receive the side 120 wall between the seats therein, a front cross member disposed facing inwardly and having inwardly offset ends disposed on the inner sides of said side wall front flanges, gaskets arranged between said overlapping front flanges, securing bolts for said overlapping front flanges, and corner irons bolted to said top and side walls and to said front flanges thereof. 125 130

5. An oven comprising side walls having inwardly projecting flanges at their front edges, a top having downwardly projecting flanges at its front and side edges, the front flanges of said top and side walls being angled, the upper ends of said side walls and of their said front flanges being inwardly offset providing seats for the overlapping side and front flanges of said top, the inwardly projecting arms of said top and side wall front flanges being cut away at the ends thereof permitting the overlapping engagement of such flanges, said top wall being notched at its corners to receive the side wall between the seats therein, a front cross member having inwardly offset ends disposed on the inner sides of said side wall front flanges, the inwardly projecting arms of such flanges being cut away to receive the said offset ends, securing bolts for said overlapping front flanges and said cross member, and corner irons secured to said top and side walls. 70
- 10 6. An oven comprising side walls having inwardly projecting flanges at their front edges, a top having downwardly projecting flanges at its front and side edges, the upper ends of said side walls and of their said front flanges being inwardly offset providing seats for the overlapping side and front flanges of said top, securing bolts for said overlapping front flanges, and corner irons secured to said top and side walls. 80
- 15 7. An oven comprising side walls having inwardly projecting flanges, a top having downwardly projecting flanges at its front and side edges disposed with its side flanges overlapping the upper ends of the top walls and its front flange overlapping the upper ends of the front flange, the underlying front flanges being inwardly offset to provide seats for the overlying flanges, and securing bolts for said flanges. 90
- 20 8. An oven comprising side walls having inwardly projecting flanges at their front edges, a top having downwardly projecting flanges at its front and side edges, the side flanges overlapping the sides which are inwardly offset to receive the same, the front flange of the top overlapping the upper ends of the front flanges of the sides which are inwardly offset to receive the same, a front cross member having inwardly offset ends disposed on the inner sides of said side wall front flanges, gaskets arranged between said overlapping front flanges and said front flanges and cross member, and securing bolts for said overlapping front flanges and for said cross member. 100
- 25 9. An oven comprising side walls having inwardly projecting flanges at their front edges, a top having downwardly projecting flanges at its side and front edges disposed with its side flanges overlapping the upper ends of the side walls and with its front flange overlapping the upper ends of said side wall front flanges, the upper ends of said front flanges being inwardly offset to provide seats for the overlapping top flange, gaskets arranged between the overlapping parts of said flanges, and bolts clamping said flanges with the gaskets between the same, and corner irons bolted to said top and side walls and to their said front flanges, the holes for at least one of the bolts of each corner iron being of a size permitting limited movement of the parts. 110
- 30 10. An oven comprising side walls having inwardly projecting flanges at their front edges, a top having downwardly projecting flanges at its side and front edges disposed with its side flanges overlapping the upper ends of the side walls and with its front flange overlapping the upper ends of said side wall front flanges, gaskets arranged between the overlapping parts of said flanges, bolts clamping said flanges with the gaskets between the same, and corner irons bolted to said top and side walls and to their said front flanges, the holes for at least one of the bolts of each corner iron being of a size permitting limited movement of the parts. 120
- 35 11. An oven comprising side walls having inwardly projecting flanges at their front edges, a top having downwardly projecting flanges at its side and front edges disposed with its side flanges overlapping the upper ends of said side flanges and its front flange overlapping the upper ends of said side wall front flanges, the upper ends of said side wall front flanges being inwardly offset to provide seats for the overlapping top flange, gaskets arranged between the overlapping parts of said flanges, and bolts clamping said flanges with the gaskets between the same. 130
- 40 12. An oven comprising side walls having inwardly projecting flanges at their front edges, a top having downwardly projecting flanges at its side and front edges disposed with its side flanges overlapping the upper end of the side walls and with its front flange overlapping the upper ends of said side wall front flanges, the upper ends of said front flanges being inwardly offset to provide seats for the overlapping top flanges, gaskets arranged between the overlapping parts of said flanges, and corner irons secured to said top and side walls. 140
- 45 13. An oven comprising side walls having inwardly projecting flanges at their front edges, and a top having downwardly projecting flanges at its side and front edges disposed with its side flanges overlapping the upper ends of said side wall front flanges, the upper ends of said front flanges being inwardly offset to provide seats for the overlapping top flange. 150
- 50 14. An oven comprising side walls having inwardly projecting flanges at their front

edges, a top having downwardly projecting flanges at its side and front edges disposed with its side flanges overlapping the upper ends of the side walls and with its 5 front flange overlapping the upper ends of said front flanges thereof, the upper ends of said front flanges being inwardly offset to receive said overlapping top flange, the corners of said top being notched to receive 10 the corners of said side walls between said offsets.

15. The combination in a stove comprising a back wall provided with a shelf at the top thereof, a shelf back wall, bolts disposed through said stove back wall and clamped thereto by nuts, said shelf back wall having openings therein of such size

as to embrace said nuts, concavo convex disks disposed on said bolts to face inwardly with their edges engaging said shelf back 20 wall, and clamping nuts for said disks.

16. In a stove, the combination of coacting overlapping parts, a bolt arranged through one of said parts and clamped thereto by means of a nut on said bolt, the other part having an opening of such size as to embrace said nut, a concavo convex disk arranged on said bolt to face inwardly with its edges engaging the part having said opening therein, and a clamping nut for said 30 disk.

In witness whereof, I have hereunto set my hand.

ALFRED J. REEDY. [L.S.]
